(74) Attorney, Agent, or Firm — Hemisphere Law, PLLC;
Zhigang Ma(57) **CLAIM**

The ornamental design for a hair straightening apparatus, as shown and described.

DESCRIPTION

FIG. 1 is a perspective view of a hair straightening apparatus, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line shown are included for the purpose of illustrating portions of the hair straightening apparatus which form no part of the claimed design.
